UNITED STATES PATENT OFFICE

152,198

DESIGN FOR A PULL FOR DOORS AND THE LIKE

Daniel C. Hay, Santa Monica, Calif.

Application December 17, 1946, Serial No. 135,568

Term of patent 14 years

(Cl. D10—8)

To all whom it may concern:

Be it known that I, Daniel C. Hay, a citizen of the United States, residing at Santa Monica, county of Los Angeles, State of California, have invented a new, original, and ornamental Design for a Pull for Doors and the like, of which the following is a specification, reference being had to the accompanying drawing, forming a part thereof.

Figure 1 is a view in elevation of a pull for doors and the like, showing my new design.

Figure 2 is a view in side elevation of a pull showing my new design.

Figure 3 is a view in end elevation of a pull showing my new design.

I claim:

The ornamental design for a pull for doors and the like, as shown.

DANIEL C. HAY.
